UNITED STATES PATENT OFFICE.

MARCELLUS M. ADAMS, OF GREENFIELD, INDIANA.

GARMENT-HOLDER.

SPECIFICATION forming part of Letters Patent No. 790,337, dated May 23, 1905.

Application filed January 18, 1905. Serial No. 241,642.

To all whom it may concern:

Be it known that I, MARCELLUS M. ADAMS, a citizen of the United States, residing at Greenfield, in the county of Hancock and State of Indiana, have invented new and useful Improvements in Garment-Holders, of which the following is a specification.

My invention is a garment-holder, and more particularly a device for aiding persons to put on a coat, vest, or other garment.

The invention consists in a supporting device which engages the sleeves of the garment and holds them distended, so that the arms can be readily inserted thereinto and the garment slipped on. When not used for this purpose, the device can be employed as a garment-hook.

In the accompanying drawings, Figure 1 is a perspective view of the invention. Fig. 2 is a plan view thereof. Fig. 3 is a side elevation.

Referring specifically to the drawings, 5 denotes a bar having its outer ends bent downwardly at substantially right angles thereto, 25 as at 6, and terminating in rearwardly-presented hooks 7. The bar is secured to a wall, door, or other support 8 by staples 9, through which it loosely extends, so that the hooks can be swung outwardly for a purpose to be 30 described hereinafter. The points of the hooks are extended sidewise, as shown in Fig. 2, to give the proper direction to the sleeves of the garment.

Any suitable material can be used in the 35 manufacture of the device, such as a piece of stout wire, as shown in the drawings. The hooks are preferably reinforced to give them the necessary stiffness by bending the wire back from the points of the hooks, as shown.

40 In use the hooks will be swung out from the support and the garment placed behind the hooks, which are then inserted in the sleeves, as shown in Fig. 1. This holds the garment

in an easy position, and it can be readily slipped on without assistance, after which the hooks 45 are removed. The under coat can be adjusted by letting the body drop down a little on the hooks and then reaching back and pulling down said coat.

When not in use, the hooks hang down, as 50 shown in Fig. 3, the parts 6 and the outer ends of the hooks being in contact with the support. In this position the hooks are firmly supported, and the device can be used to hang garments on.

55 The device will be made in various sizes to suit different-sized garments. Its width can be altered by bending down the bar 5, as shown by dotted lines in Fig. 1. This brings the hooks closer together.

60 The invention is extremely simple and can be produced at a trifling cost, and it effectively serves the purpose for which it is intended.

Having thus described my invention, what 65 is claimed as new, and desired to be secured by Letters Patent, is—

1. In a garment-holder, the combination with a support, of a bar secured thereto and having its outer ends bent downwardly to extend along the support, and formed with rearwardly-presented hooks.

70 2. In a garment-holder, the combination with a support, of a bar loosely secured thereto and having its outer ends bent downwardly to extend along the support, and formed with rearwardly-presented hooks, the points of which extend sidewise and contact with the support.

75 In testimony whereof I have signed my name 80 to this specification in the presence of two subscribing witnesses.

MARCELLUS M. ADAMS.
